FUSE PLUG

Charles Peckerman, New York, N. Y.

Application August 6, 1931, Serial No. 555,501

4 Claims. (Cl. 200—130)

My present invention in certain of its broader aspects, is capable of a wide and varied range of use in connection with fuse plugs in general, but is especially adapted for embodiment in a fuse plug of the type which employs a frangible transparent handle portion or top.

The advantages of utilizing a glass topped fuse plug have long been recognized. Such plugs permit ready inspection of the fusible elements. When a number of plugs are arranged in a common fuse box ready detection of a blown fuse is possible due to the manner in which the glass becomes discolored from the products of combustion when a fusible element burns out. Furthermore they appeal to the general public because of the fact that many persons fearing electric shocks and overly cautious about replacing fuses, have much more confidence in handling a glass member than they would in handling the ordinary metallic topped plug or metal rimmed plug.

One difficulty which has heretofore been encountered in connection with the use of plugs of this character, has been the danger of the glass shattering or cracking when the fusible element burned. Such shattering occurred because of the sudden generation of an intense heat at the interior of the glass due to the metallic vapors and other products of combustion from the burning fuse, the cracking or shattering tendency being further increased by the sudden expansion of the air within the plug. Such shattering was not only productive of undesirable fire hazards, but rendered a broken plug difficult to remove without danger of injuring the fingers, unless special tools were used to extract the broken plug from its socket.

An object of the present invention is to retain all of the advantages of using the glass topped plugs and yet eliminate the danger of shattering the frangible material when a fuse blows.

Another object is to provide a plug of extremely simple, practical, rugged, durable, inexpensive construction, well suited to meet the requirements of convenient manufacture and facile removal and replacement.

Another object is to accomplish the foregoing desiderata with but slight change in the construction of a substantially conventionalized type of plug, the only new element required in accordance with one embodiment of the invention being a small heat absorbing disc of fibrous material, such as cardboard, asbestos or

the like, introduced into the interior of the plug as an incident of its manufacture.

In accordance with a preferred embodiment of the invention, the fusible element has one end anchored as usual to a terminal button secured within a socket member of porcelain or equivalent material. The other end of the fuse extends through the hollow chamber defined by the socket piece and the glass handle portion and is soldered or otherwise secured to the threaded terminal sleeve which encircles the assemblage and clamps the glass handle to the socket. The above described standard construction is modified by my invention in order to minimize the amount of fusible material which burns when an over-load of current passes therethrough. A small plate of heat absorbent material such as cardboard or the like extends transversely of the hollow interior of the plug and the fuse is led through a notch in the edge of the plate, carried across the plate closely adjacent the exposed surface of the latter and then out between the socket and the handle to the terminal sleeve. Thus the only portion of the fuse which actually burns, is a short length of wire lying substantially directly upon the cardboard and having a weakened portion therein where the break may occur. Consequently the actual amount of fusible material which burns, is less than in prior types of constructions.

The exposed surface of the cardboard itself may char or become blackened by products of combustion when the fuse element burns, but that section of the fusible element which lies below the cardboard and within the socket, will not burn and in consequence, heat generation will be minimized to such an extent that there is no danger of the glass piece cracking.

In accordance with other embodiments of the invention, substantially similar results may be obtained by the use of a transparent cardboard disposed above the link or by placing the link between two transparent cardboards. An essential distinction between this type of construction and prior devices is the fact that the present invention reduces heat generation, and permits the use of ordinary glass, thus avoiding the necessity for attempting to shield the glass from the heat or the need for using specially prepared expensive glass.

The invention may be more fully understood from the following description in connection with the accompanying drawing, wherein:

Fig. 1 is a perspective view of a fuse plug embodying the invention.

Fig. 2 is an enlarged longitudinal sectional view therethrough on the line 2—2 of Fig. 1,

Fig. 3 is a transverse sectional view on the line 3—3 of Fig. 2,

5 Fig. 4 is a perspective view of the small cardboard disc which prevents the glass from cracking, and

10 Figs. 5 and 6 are fragmentary longitudinal sectional views illustrating alternative embodiments of the invention.

Referring with particularity to the drawing, I have used the reference numeral 10 to designate the glass top or handle of the fuse plug. This member consists preferably of a manually 15 graspable upper end 11 of any suitable cross section and an integral sleeve portion 12. A socket 13 of porcelain or other insulating material is provided with an external flange 14, adapted to be held in abutting relationship with 20 the end of the sleeve 12 by the use of a threaded metallic terminal sleeve 15, having a flange 16 at one end to engage under the flange 14 and having threaded engagement with the sleeve 12, whereby the flange 14 may be drawn tightly 25 against the end of the sleeve 12 when the sleeve 15 is screwed home.

One end of the fuse 17 (typically a flat fuse wire with a weakened portion 17a) is attached in conventional fashion as by soldering at 20 to 30 a terminal button 18 spun into engagement with the bottom of the socket 13 through an opening 19 therein.

As thus far described, the plug may be substantially conventional, the present invention residing more particularly in the manner in which the fuse wire is arranged within the plug, so that only a small length thereof burns when the fuse blows and the heat generation is minimized.

40 I have illustrated a heat absorbent disc 21 of cardboard or the like, resting upon the top of the socket 13, the socket tapering inwardly as at 22 above the flange 14 and affording a shoulder 23 upon which the cardboard disc rests. 45 The fuse 17 is trained through a slot 21a at one edge of the disc, carried across the upper face of the disc in close contiguity thereto and then passed between the flange 14 and the end of the sleeve 12, being carried upwardly along the outside of the sleeve and having its end 24 lying within a flattened portion or recess 25 in the sleeve 12. The end of the fuse wire projects slightly above the top of the metallic sleeve 15 and the two may be joined together by soldering 55 ing as at 26.

The end 24 of the fuse soldered in the recess 25 not only assures a good electrical contact between the fuse and the metallic sleeve, but also prevents rotation of the metallic sleeve with 60 respect to the member 10.

It is not my intention in this application to claim the theory of operation of the apparatus above described. The construction, however, has been thoroughly tested and it has been demonstrated that the frangible top, even though 65 made of ordinary molded glass does not shatter or crack when a fuse blows. Without limiting myself therefore to any definite theory of operation, the following tentative explanation of the 70 advantageous results obtained, is offered:—

The length of fuse wire actually exposed for burning is less than in the ordinary fuse plug of this character. The only portion which actually burns and generates vapor, is that run 75 of the fuse directly overlying the cardboard.

Therefore, less heat is generated and the danger of cracking the glass lessened. Furthermore, the cardboard subdivides the otherwise capacious chamber cooperatively defined by the members 10 and 13, into two chambers.

80 The upper of these two chambers may for the sake of convenience, be termed the combustion chamber, since it is here that the actual burning of the fusible element occurs. The lower chamber may, for the sake of descriptive convenience, be referred to as the cushioning chamber, since when combustion occurs in the upper chamber, and the air therein is suddenly expanded, with an effect which is almost explosive, the cardboard disc will yield under the 85 pressure suddenly generated and render the upper chamber substantially expansible to take care of the sudden combustion which occurs therein. This cushioning effect of the lower chamber combined with the cardboard is, of course supplementary to the heat absorbing action of the cardboard or the other fibrous disc 90 which may be utilized.

95 A contributing factor is believed to be the fact that the restricted volume of the combustion chamber together with the disc which cuts it off from the cushioning chamber, both tend to minimize convection currents which in the absence of the partition forming cardboard, would aid in heating the glass.

100 During the burning of the fuse, the arc is shorter, the period of combustion is consequently shorter, the burning is in some manner choked due to the fact that the burning portion of the fuse lies directly against the heat absorbing 105 disc and the result desired is effected without in any way attempting to shield the glass itself from the heat. In other words, the desired effect is obtained not by the use of a heat insulating medium but by the use of means to 110 control and minimize the heat which is generated.

115 By using a transparent cardboard disc 20' arranged above the fuse instead of below it as shown in Fig. 5, heat generation takes place 120 almost entirely within the socket 13, which will not crack or break, even under extreme heat, yet the advantages of a visible fuse are retained. Furthermore, even with this form of the invention the arc is again choked and much 125 of the heat absorbed by the cardboard.

130 By using transparent cardboard discs 31, 32 above and below the horizontal run of the fuse wire (Fig. 6), even more effective heat absorption by the cardboard and choking of the arc is accomplished.

135 It will thus be seen that there is herein described apparatus in which the several features of this invention are embodied, and which apparatus in its action attains the various objects of the invention and is well suited to meet the requirements of practical use.

140 As many changes could be made in the above construction, and many apparently widely different embodiments of this invention could be made without departing from the scope thereof, it is intended that all matter contained in the above description or shown in the accompanying drawing shall be interpreted as illustrative and not in a limiting sense.

145 Having thus described my invention, what I claim as new and desire to secure by Letters Patent is as follows:—

1. In a fuse plug having a frangible top, a fuse wire and heat absorbing spark choking 150

plates closely adjacent to and upon opposite sides of that portion of the wire where a break occurs upon overloading of the fuse.

2. In a fuse plug having a glass top, a fuse wire and heat absorbing spark choking plates closely adjacent to and upon opposite sides of that portion of the wire where a break occurs upon overloading of the fuse, the upper of said elements being transparent whereby the condition of the fusible element may be observed through the glass top.

3. A glass topped fuse plug, having a fusible

element therein and a transparent heat absorbing plate overlying that portion of the fusible element at which an arc occurs when the fuse blows.

4. A glass topped fuse plug, having a fusible element therein and a transparent heat absorbing member overlying that portion of the fusible element at which an arc occurs when the fuse blows, said means comprising a transparent cardboard element shielding the glass top from the direct heat of the fuse.

CHARLES PECKERMANN.
